Primary Examiner — Clare Ann Gannon(74) Attorney, Agent, or Firm — Banner & Witcoff, Ltd.(57) CLAIM

The ornamental design for a shoe, as shown and described.

DESCRIPTION

FIG. 1 is a front perspective view of a shoe showing my new design in a first state;

FIG. 2 is a side view thereof;

FIG. 3 is a rear perspective view thereof;

FIG. 4 is a front perspective view from the opposite side of the shoe shown in a second state; and,

FIG. 5 is a top view thereof.

The even-length broken lines represent stitching that forms no part of the claimed design. The five unshaded rectangular regions bounded by even-length broken lines form no part of the claimed design. The uneven-length broken lines depicting the lacing and the remainder of the shoe form no part of the claimed design.
